UNITED STATES PATENT OFFICE.

ROY HERBERT CUNNINGHAM, OF JACKSON, MICHIGAN, ASSIGNOR TO THE REYNOLDS SPRING COMPANY, OF JACKSON, MICHIGAN.

ELECTRIC SWITCH.

Application filed July 15, 1927. Serial No. 205,952.

The invention relates to improvements in electric switches.

The object of the present invention is to improve the construction of electric switches equipped with snap switch mechanism actuated by a push slide and to provide a simple, practical and efficient electric switch of this character of increased strength and durability adapted to enable both wires of a 10 cord to be severed and connected by binding screws to the switch.

Another object of the invention is to provide an electric switch of this character equipped at both ends with a pair of binding 15 screws and an embedded bus-bar connecting one of the members of each pair of binding screws and adapted to enable both of the wires of an electric cord to be severed and with the 20 ends of the wires at the severed portions of the cord to be secured to the binding screws, thereby eliminating the wear and cutting through of the continuous wire of an electric cord when only one of the wires thereof is 25 severed and connected to the binding screws and an electric switch.

With these and other objects in view, the invention consists in the construction and novel combination and arrangement of parts hereinafter fully described, illustrated in the accompanying drawings and pointed out in the claims hereto appended, it being understood 30 that various changes in the form, proportion and minor details of construction, within the scope of the claims may be resorted to without departing from the spirit or sacrificing any of the advantages of the invention.

In the drawings:—

Figure 1 is a side elevation of an electric switch constructed in accordance with this invention, the cap section of the casing being 40 removed.

Fig. 2 is a central transverse sectional view of the electrical switch.

Fig. 3 is an elevation of the cap section 45 showing the inner face of the same.

Fig. 4 is a detail transverse sectional view illustrating the manner of mounting the swinging switch member.

Fig. 5 is a detail perspective view of the 50 push slide.

Fig. 6 is a detail perspective view of the fixed support.

Fig. 7 is a detail longitudinal sectional 55 view of the solid section of the casing on a reduced scale.

In the accompanying drawing in which is illustrated the preferred embodiment of the invention, the electric switch is provided with a casing of substantially cylindrical form divided longitudinally into two approximately semi-cylindrical sections 1 and 2, the section 1 being substantially solid and the section 2 consisting of a shell and forming a cap section as clearly illustrated in Fig. 2 of the drawings. The casing is designed to be constructed of molded insulating material such as bakelite and the sections are provided at their ends with semi-circular recesses 3 and 4 forming circular openings for the severed end portions of an electric cord (not shown) containing the conductor wires. The walls of the recesses 3 and 4 are rounded as shown and the section 1 is provided at its ends with seats 5 and 6 arranged in pairs at opposite sides of the section and separated by intervening recesses 7 which provide ample space for the severed ends of the electric cord. The seats 6 at one side of the section 1 receive binding screws 8 which are connected by a bus-bar or conductor bar 9' embedded in the insulating material of the solid section as shown at the lower right hand portion of Fig. 2 of the drawing and in dotted lines in Fig. 1. The other two seats receive binding screws 9 and attaching portions 10 of relatively stationary 80 switch contacts 11. All of the screws of the switch are designed to engage metal bushings substantially similar to bushings 12 to which a fixed support 13 is secured by screws 14 and the attaching portions 10 of the stationary 85 switch contacts are preferably riveted to the metal bushings which are engaged by the binding screws 9. By employing pairs of binding screws at the ends of the casing as shown, both wires of an electric cord may be 90 cut and secured to the electric switch by the said binding screws and the wear and difficulty experienced in switches provided with only one set of binding screws and where only one wire is cut are avoided. Where one of 95 the wires in an electric cord is left continuous, it is liable to become broken through the operation of snap switch mechanism.

The relatively stationary switch contacts 11 are spaced apart and have inclined terminal contact portions to cooperate with a swinging switch member 15 which is carried by the snap switch mechanism hereinafter described, to and from the position illustrated in Fig. 2 of the drawing. The station- 100 105 110

ary switch contacts are resilient and are engaged by the movable switch member with a wiping action which secures a proper electrical connection and keeps the contacts clean and free from accumulations. The upper ends 16 of the stationary switch contacts are bent outwardly slightly to provide a flaring entrance and prevent the swinging switch member from striking the end edges of the stationary switch contacts. The swinging switch member 15 consists of an approximately inverted yoke composed of spaced sides and a connecting transverse portion 17 which is depressed at the center to form loop shaped extensions 18 which engage at their outer sides with the stationary switch contacts. The transverse connecting portion 17 is provided with a central guide opening 19 in which slides the upper end of a pin or rod 20 mounted at its lower end in a perforation 21 of a rocking plate 22 and provided at its lower end with a stop collar 21^a arranged upon the rocking plate. The rocking plate 22 is provided at its ends with journals 23 mounted in open bearings 24 of a push slide 25 which shifts the position of the rocking plate to move the lower end of the same and a coiled spring 26 to opposite sides of the center or axis of the swinging switch member for causing the switch to snap. The sides of the swinging switch member are provided with pivots or journals 27 which are preferably formed integral with the said sides of rigidly connected therewith. The pivots or journals extend inwardly from the sides of the swinging switch member and are mounted in bearing openings 28 of the fixed support 13. The fixed support 13 consists of an open box or casing constructed of sheet metal or other suitable material and composed of a bottom, side and end walls, the side walls being provided with centrally arranged upwardly projecting ears 29 having the bearing openings 28. The said side walls are also provided at their ends with upwardly extending arms 30 having laterally projecting outwardly extending terminal stop lugs 31 formed by bending the arms at right angles and arranged to limit the swinging movement of the movable switch member. When the swinging switch member is in its circuit closing position in engagement with the stationary switch contacts the said member is also in engagement with one pair of the stop lugs 31 and when the swinging switch member is moved to its upper position it is in contact with the other pair of stop lugs 31.

The push slide consists of a channel bar composed of a bottom and side flanges which are provided with central rectangular extensions 32 having the bearings 24 and vertical entrance slots 25. The bottom of the push slide is provided with spaced depending lugs 33 formed integral with the said bottom by bending portions of the same downward-

ly and extending across the bottom and adapted to engage the end walls 34 of the fixed support 13 which forms a guide for the push slide. The push slide rests upon the upper edges of the end walls and slides between the side walls and is limited in its movement by the engagement of transverse lugs 33 with the said end walls 34. The push slide is equipped at its ends with insulating knobs or buttons 35 of molded bakelite or other suitable material. One of the push buttons 35 is designed to be red and the other of black or some contrasting color for indicating readily when the switch is on or off. The solid section 1 of the casing is provided with a transverse groove or space 36 to receive the push slide and it has transversely aligned recesses 37 forming side openings through which the push buttons 35 extend and operate. The movement of the push slide in carrying the spring 26 from one side of the center or pivot of the movable switch member to the other compresses the spring and causes the movable switch member to spring or snap into "on" and "off" position. The fixed support is rigidly secured to the section 1 by the screws 14 which pierce the bottom of the fixed support and engage the metal bushings 12.

The sections 1 and 2 are secured together by screws 38 having their heads countersunk in openings 39 of the section 1 and their threaded portions engaged with metal bushings 40 embedded in solid portions of the cap or shell section 2 of the casing.

What is claimed is:

1. An electric switch including an insulating casing, spaced stationary switch contacts, a transversely disposed support fixed to the casing and having spaced side and end walls, the side walls being extended above the end walls, a push slide arranged to slide upon the end walls above the bottom of the support and guided between the side walls of the fixed support and provided with depending means projecting into the support from the slide towards the bottom of the support and operating between the end walls and arranged to engage the end walls to limit the sliding movement of the push slide, a swinging switch member pivotally mounted on the support and movable to and from the stationary contacts, and resilient means connecting the push slide with the swinging switch member and arranged to be carried to opposite sides of the pivot of the swinging switch member to cause the same to snap or swing into and out of engagement with the stationary switch contacts.

2. An electric switch including an insulating casing, spaced stationary switch contacts, a transversely disposed support fixed to the casing and having spaced side and end walls, a push slide arranged to slide upon the end walls above and spaced from the bottom of the

support and provided with spaced lugs formed by bending the metal of the slide and which project from the slide towards the bottom of the support, and adapted to engage 5 with the inner faces of the end walls of the support to limit the movement of the push slide, and yieldable means for connecting the push slide with the swinging switch member.

3. An electric switch including an insulating casing, spaced stationary switch contacts, a transversely disposed support fixed to the casing and having spaced side and end walls, the side walls being extended above the end walls, a push slide consisting of a channel 10 bar having a bottom and side flanges, the side flanges being provided with extensions having open bearings, said push slide being arranged upon the end walls of the fixed support and having spaced depending lugs operating 15 between the end walls and engaging with the same to limit the movement of the slide, a swinging switch member pivoted on the support and movable to and from said contacts, a rocking plate pivotally mounted 20 in the open bearings of the extensions of the slide, a pin supported at its lower end in the rocking plate and slidable in the swinging switch member, and a coiled spring disposed 25 on the pin and interposed between the swinging switch member and the rocking plate.

4. An electric switch including an insulating casing, spaced stationary switch terminals mounted within the casing, a transversely disposed support fixed to the casing and composed of a bottom, side and end walls, the side walls being extended above the end walls and provided with central bearings and terminal arms having outwardly extending laterally projecting lugs, a swinging switch 30 member consisting of an inverted yoke composed of spaced sides and a connecting top portion, the sides being provided at their lower ends with inwardly extending pivots fitting in the bearings of the fixed support, and the transverse top portion being depressed to form loop extensions and provided with a central opening, a push slide guided 35 between the sides of the support and arranged upon the end walls thereof and composed of a channel bar having depending integral transverse lugs operating between the

end walls of the fixed support and arranged to engage the same, said push slide being provided with centrally arranged side extensions having open bearings, a rocking plate 55 arranged between the extensions and having journals mounted in the open bearings thereof, said rocking plate being provided with a perforation, a pin mounted at one end in the perforation of the rocking plate and guided 60 at its upper end in the opening of the transverse portion of the yoke, and a coiled spring disposed on the pin and interposed between the transverse portion of the yoke and the rocking plate. 65

5. An electric switch including an insulating casing, a pair of terminal binding screws arranged at each end of the casing, switch mechanism for electrically connecting one member of each pair of binding screws and for breaking the electrical connection between the same, and a bus-bar embedded in the insulating material of the casing, and forming a permanent continuous electrical connection between such binding screws, said binding 70 screws permitting both wires of an electric cord to be severed and the terminals of the wires of the severed portions attached to the switch. 75

6. An electric switch including an insulating casing, spaced switch contacts, a support fixed to the casing, a push slide arranged to slide upon the support in spaced relation to the bottom of the support and provided with means intermediate the ends of the same and 80 projecting into the support toward the bottom of the support and terminating short of the bottom of the latter and adapted to engage portions of the support to limit the sliding movement of the slide, a switch member 85 swingingly connected to said support and movable to and from said contacts, and means connecting the push slide and the switch member and arranged to be carried to opposite sides of the point of swinging connection of the switch member to the support to cause the latter to snap into and out of engagement 90 with said switch contacts. 95

In testimony whereof I have hereunto set my hand.

ROY HERBERT CUNNINGHAM.
